(57) **CLAIM**

The ornamental design for a hanging light fixture as shown and described.

DESCRIPTION

FIG. 1 is a front view of a hanging light fixture, showing the new design;

FIG. 2 is a rear view thereof;

FIG. 3 is a top view thereof;

FIG. 4 is a bottom view thereof;

FIG. 5 is a left side view thereof;

FIG. 6 is a right side view thereof;

FIG. 7 is perspective front, top, right view thereof;

FIG. 8 is a perspective front, top, left view thereof;

FIG. 9 is a perspective rear, top, right view thereof;

FIG. 10 is a perspective rear, top, left view thereof;

FIG. 11 is a perspective front, bottom, right view thereof;

FIG. 12 is a perspective front, bottom, left view thereof;

FIG. 13 is a perspective rear, bottom right view thereof; and,

FIG. 14 is a perspective rear, bottom left view thereof.

The broken lines show portions of the hanging light fixture that form no part of the claimed design.

1 Claim, 11 Drawing Sheets
